UNITED STATES PATENT OFFICE.

CHARLES L. HILL, OF SAN FRANCISCO, CALIFORNIA.

DESIGN FOR A DISPLAY CABINET.

Application filed August 3, 1928. Serial No. 27,697. Term of patent 7 years.

To all whom it may concern:

Be it known that I, CHARLES L. HILL, a citizen of the United States of America, residing at San Francisco, in the county of San Francisco and State of California, have invented a new, original, and ornamental Design for Display Cabinets, of which the following is a specification, reference being had to the accompanying drawing, forming a part thereof.

Figure 1 is a front elevation of my design, and

Figure 2 is an edge elevation of the same.
I claim:

The ornamental design for a display cabinet substantially as shown.

CHARLES L. HILL.
